(57) **CLAIM**

The ornamental design of an insert for support beam, as shown and described.

DESCRIPTION

FIG. 1 is a front perspective view of a first embodiment of an insert for support beam;

FIG. 2 is a top view thereof, the bottom view being a mirror image;

FIG. 3 is a right side view thereof, the left side view being a mirror image;

FIG. 4 is a front view thereof, the rear view being a mirror image;

FIG. 5 is a front perspective view thereof positioned within a support beam of a first design;

FIG. 6 is a front perspective view thereof positioned within a support beam of a second design;

FIG. 7 is a front perspective view thereof positioned within a support beam of a third design;

FIG. 8 is a front perspective view of a second embodiment of an insert for support beam;

FIG. 9 is a front view thereof, the rear view being a mirror image;

FIG. 10 is a front perspective view of a third embodiment of an insert for support beam;

FIG. 11 is a front view thereof, the rear view being a mirror image;

FIG. 12 is a front perspective view of a fourth embodiment of an insert for support beam; and,

FIG. 13 is a front view thereof, the rear view being a mirror image.

The insert for support beam is shown with a symbolic break in its length. The appearance of any portion of the article between the break lines forms no part of the claimed design. The support beams shown in FIGS. 5-7 in broken line are provided to denote certain environments of the insert, wherein the support beam shown in broken line forms no part of the claimed design.
